COMBINATION WRITING INSTRUMENT
AND SHAVER'S KITHarry I. Schwartz and Joseph H. Rothstein,
New York, N. Y.

Application July 14, 1934, Serial No. 735,112

3 Claims. (Cl. 30—47)

This invention relates to a combination writing instrument and shaver's kit.

One of the main objects of the invention resides in a writing instrument such as a fountain pen or mechanical pencil of a size to be conveniently carried in the pocket of the owner, and in which a shaver's kit is compactly carried for instant use when desired. Such an article will be found useful by business men and other persons who may desire to shave themselves when occasions arise which prevent them from using their regular shaving requisites.

Another feature of the invention is to utilize a portion of the tubular body of a writing instrument in which a safety razor, shaving brush, and a supply of shaving soap or razor blades may be compactly stored without adding undue weight to the instrument and without interfering with the mechanical working or use thereof.

Another feature resides in a safety razor including a cylindrical handle and a head, the head being foldable to a position to lie within the confines of the diameter of the handle to enable insertion of the entire folded razor into a cylindrical barrel of a diameter sufficient to snugly receive the same.

A further feature of the invention is to provide a safety razor of the cross head type which may be folded to a position parallel to the longitudinal axis of its handle, and which may be securely held in a shaving position for use.

While several objects of the invention have been set forth above, other objects reside in the novel construction, combination and arrangement of parts, the essential features of which are hereinafter fully described in the following specification, are particularly pointed out in the appended claims, and are illustrated in the accompanying drawings, in which:

Figure 1 is a side elevational view of the preferred embodiment of the invention.

Figure 2 is an enlarged vertical longitudinal sectional view on the line 2—2 of Figure 1.

Figure 3 is a horizontal sectional view on the line 3—3 of Figure 1.

Figure 4 is a vertical sectional elevational view illustrating the manner by which the ink sack of the fountain pen is filled.

Figure 5 is a fragmentary detail perspective view of the ink sack.

Figure 6 is a view partly in elevation, and partly in vertical section illustrating the manner in which the shaving kit is compactly stored in the writing instrument.

Figure 7 is a sectional elevational view of the razor ready for use.

Figure 8 is a vertical transverse sectional view on the line 8—8 of Figure 7.

Figure 9 is a side elevational view of the shaving brush extended for use.

Figure 10 is an enlarged vertical sectional view on the line 10—10 of Figure 9.

Figure 11 is a front elevational view of the razor with a modified form of handle.

Figure 12 is a side elevational view of a modification showing the razor kit associated with a mechanical pencil.

Figure 13 is an enlarged detail sectional view on the line 13—13 of Figure 12.

Figure 14 is a horizontal sectional view on the line 14—14 of Figure 13.

Referring to the drawings by reference characters, and more particularly to the construction shown in Figures 1 to 10 inclusive, the numeral 10 designates a fountain pen which includes a cylindrical barrel 11, and threaded in one end of the barrel as at 12, is a collar 13 forming part of the nib section of the pen and into which collar the pen point 14 extends, and which is adapted to receive ink from a rubber ink sack 15, the open end of the sack 15 telescoping a reduced annular flange 16 at the inner side of the collar 13 and being fixedly secured thereto. Encircling the sack 15 is a coil spring 17, one end of which abuts the collar 13 while the other end of the spring extends through an opening in an ear 18 molded on the closed end of the sack 15. Thus it will be seen that the spring 17 tends to normally hold the sack 15 in an extended position, but permits of the compression of the sack for filling the same through the nib end of the pen in a manner to be presently explained.

Threaded into the barrel 11 at that end thereof opposite to the end in which the collar 13 is threaded, is one end of a tubular holder 19, the threading connection between the holder and the barrel being designated at 20. The tubular holder 19 is open at its outer end and closed at its inner end, the closed end being provided with a concavity 21 to receive the closed rounded end of the sack 15 when the holder 19 is utilized as a plunger for compressing the sack 15 against the tension of the spring 17. By screwing inwardly upon the tubular holder 19, the threaded connection between the holder and the barrel will be broken whereupon the closed end of the holder 19 may be utilized as a plunger for compressing the sack 15 in the manner shown in Figure 4 of the drawing. When the nib section of

the pen is inserted into a supply of ink and the sack 15 compressed in the manner just described, release of the holder 19 permits the spring 17 to return the sack and holder to a normal position, 5 which at the same time creates a suction within the sack sufficient to draw up a supply of ink therein. After a filling operation, the tubular holder 19 is again turned to effect the threaded connection 20 between the barrel 11 and the said holder to assume the position shown in Figure 10 2 of the drawings.

Threaded to the nib end of the barrel 11 is a cap 22, the inner walls of which are tapered as at 15 23 to facilitate frictional engagement of the said wall with the outer open end of the tubular holder 19 as shown in Figure 4. This is the position of the cap when the nib end of the pen is exposed for use. The external diameter of the cap 22 is the same as the external diameter of the barrel 11 and carried by the cap 22 is a clip 24, the ring portion 25 of which overlaps the open threaded end of the cap so as to overlap the joint between the cap 22 and the nib end of the barrel 11. The clip 24 is utilized for the fastening of 25 the article to the wall of the pocket of the owner.

Normally stored within the tubular holder 19 is a shaver's kit which includes a folding razor shown in set up position for use in Figure 7 and in a folded position in Figures 2 and 6. The 30 safety razor includes broadly a handle and a head. The handle consists of a cylindrical hollow section 26, the same being open at its outer end and closed at its inner end and of an external diameter to snugly slide into the tubular holder 19. Threaded to the lower open end of the handle section 26 is a lower handle section which 35 comprises a casing 27 housing an extendable shaving brush 28. The outer end of the casing 27 exteriorly thereof is provided with screw threads 29 40 for threading engagement with screw threads 30 provided on the inside of the outer end of the tubular holder 19.

The head section of the safety razor includes a 45 relatively thick blade rest or carrier 31 having opposite flat sides which are provided with closely arranged guard teeth or ribs 32 formed by spaced channels cut transversely of the flat faces and a longitudinal recess 33 provided in the convex top side thereof. A safety razor blade 50 is designated at 34 and has a longitudinal slot 35 for the passage of a rib 36 extending inwardly from the blade clamping head 37, the said rib extending lengthwise of the convex top of the 55 clamping head and fitting into the recess 33 of the blade carrier 31. Fixed to the underside of the clamping head 37 centrally thereof is one end of a threaded stud 38, the same extending through a slot 39 in the blade carrier 31. The projecting end of the threaded stud 38 is cut away to provide an ear 40, while fitting against the ear 40 is an ear 41 formed on the outer end of a threaded stud 42, the ears 40 and 41 being pivotally connected by a pivot pin 43. The threaded studs 38 60 and 42 are of uniform diameter and when in a position in axial alignment, the same may be locked together by turning of the rod 43, the outer end of which is provided with a threaded socket 44. When the rod 43 is turned so that the 65 socket end overlaps the pivot joint between the threaded studs 38 and 42, the end of the rod 43 seats against the under side of the blade carried 70 31, thus locking the razor head against movement and serving to clamp the clamping head 37 down upon the carrier 31 with the razor blade 34

interposed therebetween. The flat underside of the blade carrier 31 is provided with a central longitudinal channel 68 to accommodate the rod 43 when the head of the razor is swung to a folded position parallel to the handle thereof. By unscrewing the rod 43 to uncover the pivot joint between the threaded studs 38 and 42, the razor head may be broken or turned so as to lie parallel to the rod 43 as shown in Figure 2 of the drawings. 10

The rod 43 is detachably associated with the closed end of the handle section 26 and when the razor is set up for use, the reduced threaded end 45 of the rod is threaded into a threaded recess 46 in the closed end of the handle section 26 as 15 best seen in Figures 7 and 8. However, when the head of the razor is folded to the position parallel to the rod 43 as shown in Figures 2, 3, and 6, the reduced threaded end 45 of the rod 43 is threaded into an offset threaded opening 47 in the closed 20 end of the handle section 26. By threading the rod 43 into the opening 47, the razor head when folded lies within the confines of the closed end of the handle section 26 to facilitate the insertion 25 of the razor into the tubular holder 19. 25

The top end of the shaving brush casing 27 is provided with a reduced threaded portion 48 for threading engagement into the open end of the tubular handle section 26. Thus when the sections 26 and 27 are threaded together, they provide a lower handle section of 30 uniform diameter to snugly slide into the tubular holder 19. Soap tablets 49 may be contained within the hollow handle section 26 to provide 35 soap lather for shaving and which is applied to the face of the user by the brush 28.

For securing the razor within the tubular holder 19, the lower end of the brush holder 27 is externally screw threaded as at 29 for threading engagement with threads 30 on the inside of the 40 open end of the holder 19.

The brush 28 is extendable beyond one end of the brush holder 27 and is movable to a position thereinto, the mechanism being similar to that now employed in lipsticks and the like. Fixed 45 within the holder casing 27 is the tubular sleeve 51, the same having a spiral groove 52 extending the length thereof. Fitting into the sleeve 51 and rotatable relative thereto, is a sleeve 53, the same being provided with a longitudinal slot 54, the outer end of the sleeve 53 terminating in a manipulating head 55. The brush 28 includes a cup shaped base 56 into which the bristles fit, there being a pin 57 extending outwardly from the base 56 through the slot 54 and into the spiral groove 55 52. It will thus be seen that by turning the manipulating head 55, the brush 28 may be moved to a retracted position within the casing 27 or to an extended position therebeyond for use as 60 shown in Figure 10 of the drawings. 60

The construction of the razor head is somewhat similar to the conventional Gillette type, but by providing the guard fingers 32 in relatively close formation, we find that the individual hairs to be cut are supported in a position to be acted upon by the cutting edge of the blade, and as a result a closer and cleaner shave may be obtained. Also, the close spacing of the guard fingers tends to prevent the skin from entering between the guard fingers, thus reducing the danger 70 of cutting the skin as the razor is drawn thereover.

In Figure 11 of the drawings, we have illustrated a slightly modified form in which the con- 75

struction is substantially identical to that before described, but wherein a single tubular handle section 58 is provided instead of the two sections 26 and 27 hereinbefore mentioned. The tubular handle 58 is open at its lower end and closed by a screw cap 59, the exterior of the handle being provided with screw threads 51' to facilitate threading engagement with the threads 30 on the tubular holder 19. The razor head is connected to the closed end of the tubular handle 58 in the same manner as hereinbefore described. Soap in stick form or a small tube of shaving cream may be stored within the tubular handle 58.

In Figures 12 to 14 inclusive, we have illustrated a shaver's kit in association with a mechanical pencil 60 and to which a tubular casing 61 is threadedly connected as at 62. The casing 61 is divided by a partition 63 into a compartment 64 in which the razor, shaving brush, and soap may be contained, and into a compartment 65. The compartment 65 is in turn divided into three longitudinal compartments by a partition structure 66, the center compartment containing a supply of the safety razor blades 34 for use in the safety razor, whereas the other two compartments may contain sticks of lead 67 for use in the mechanical pencil 60.

Although we have illustrated our compact shaver's kit in association with a writing instrument in the form of a pen or pencil, it will be understood that the razor, brush and a supply of soap may be inserted in a plain tube, the equivalent of the holder tube 19 and the said tube compactly carried in the pocket of the owner, or packed in a traveling bag to take up a minimum amount of space.

While we have shown and described what we consider to be the most practical embodiments of our invention, we wish it to be understood that such changes as come within the scope of the appended claims may be resorted to if desired.

Having thus described the invention, what we claim as new and desire to secure by Letters Patent of the United States, is:—

45 1. A safety razor comprising a handle, a threaded socket formed in one end of said handle, a blade carrier, a blade clamping head, a threaded stud fixedly carried by said clamping head and freely passing through an opening in said blade carrier, said stud comprising two piv-

totally connected sections, said threaded stud being threaded into said socket whereby threading of said stud home into said socket by turning said head relative to said handle or vice versa will cause said socket, to overlap the joint between said stud sections and engage the underside of said blade carrier to secure the carrier and head in clamped engagement crosswise of said handle, and partial unscrewing of said stud or handle to cause said socket to clear the joint between said studs will release the clamping tension on said blade carrier and clamping head and permit of the swinging of said blade carrier and clamping head to a position parallel to said handle. 15

2. A safety razor comprising an elongated blade carrier having flat longitudinal sides and a convex top, means for clamping a cutting blade against the convex top of said carrier, and relatively thin closely equidistantly spaced parallel 20 guard fingers provided along at least one of the flat sides of said carrier and extending from the convex top sides to the opposite under sides thereof, the spacing between said guard fingers 25 approximately the width of a hair whereby individual hairs may enter the spaces between said guard fingers and be braced by adjacent sides thereof, and the skin of a user prevented from entering the spaces between said guard fingers 30 during a shaving operation.

3. A safety razor comprising a lower handle section, a reduced upper handle section connected to one end of said lower handle section but offset with respect to the longitudinal axis 35 thereof, a razor head pivoted to the reduced upper handle section and having a longitudinal groove in the under side thereof, whereby said head may be swung to a folded position parallel to the reduced upper handle section with the reduced handle section disposed within said groove 40 to enable the folded head to compactly lie within the plane of the sides of the lower handle section, and means for locking the head and upper reduced handle section against pivotal movement after the head has been swung to a position 45 for use crosswise of said upper handle section.

HARRY I. SCHWARTZ.

JOSEPH H. ROTHSTEIN.
